ris-Seybold-Potter Company, Cleveland, Ohio,
a corporation of Delaware

Application November 26, 1934, Serial No. 754,838

54 Claims. (Cl. 101—139)

This invention relates to improvements in printing presses, particularly printing presses of the bed and cylinder type wherein the bed reciprocates and the cylinders move up and down to produce the impression on the printing stroke and to ride clear of the bed on the return stroke. More especially the present invention has to do with two-color presses of the kind indicated, and with means for rotating the cylinders and trans-
ferring sheets in such manner as to provide accurate register for the two colors.

One of the objects of the invention is the provision of driving mechanism wherein the gears employed may be simple in character and well adapted to produce accurate travel of the sheets with respect to the bed and the two color forms carried thereby.

Another object of the invention is the provision of novel means for raising and lowering the impression cylinders and for interrupting the up and down movement of these cylinders and holding them in their raised position, such means including provision for holding either one of the cylinders singly in raised position while the press continues to operate for the printing of sheets in one color.

Still another object is the provision of novel and efficient mechanism for accomplishing the foregoing objects.

Other objects and features of novelty will appear as I proceed with the description of those embodiments of the invention which, for the purposes of the present application, I have illustrated in the accompanying drawings, in which

Fig. 1 is a side elevation, partly diagrammatic, of a printing press embodying the invention.

Fig. 2 is a plan view with certain parts broken away to more clearly disclose a portion of the bed motion mechanism.

Fig. 3 is a fragmental elevation of the opposite side of the press from that shown in Fig. 1, and disclosing particularly the raising and lowering means for the impression cylinders and the control therefor.

Fig. 4 is a plan view of the mechanism shown in Fig. 3, but with the impression cylinders removed.

Fig. 5 is an end elevational view, with one of the Oldham couplings shown in central vertical section.

Fig. 6 is a fragmental plan view, partly in horizontal section upon the line 6—6 of Fig. 5.

Fig. 7 is a plan view on a larger scale, corre-

sponding with a portion of Fig. 4, the view being partly in section upon line 7—7 of Fig. 8.

Fig. 8 is a vertical sectional view, taken substantially on the line 8—8 of Fig. 7, showing the impression cylinder control mechanism in normal running condition.

Fig. 9 is a view similar to Fig. 8, taken substantially on the line 9—9 of Fig. 7.

Fig. 10 is a further view similar to Figs. 8 and 9 taken substantially on the line 10—10 of Fig. 7.

Figs. 11, 12 and 13 are fragmental vertical views, partly in section, showing the control mechanism for the second color impression cylinder in three different stages of action following the setting of the hand control lever to "off" position.

Fig. 14 is a front view on a larger scale of the hand control lever and associated parts.

Fig. 15 is a side view of the same.

Fig. 16 is a diagrammatic perspective view illustrating the impression cylinder raising and lowering means.

Fig. 17 is a similar view of the control mechanism which acts either automatically or by manual operation to disable the cylinder raising and lowering means for either one or both of the impression cylinders.

Fig. 18 is a diagrammatic view from the side of the machine shown in Fig. 3, illustrating the positions of the printing forms and impression cylinders at the time the first color begins to print.

Figs. 19 and 20 are detailed views of the first and second color cylinder raising and lowering cams respectively, these cams being shown substantially in the positions in which they appear in Figs. 8, 9 and 10.

Figs. 21 and 22 are detailed views of the first and second color impression control cams respectively, illustrated in the position they occupy just prior to the beginning of the disabling of the first color cylinder.

Fig. 23 is a fragmental detailed view illustrating in an exaggerated manner the eccentric arrangement of the gear upon the transfer cylinder.

Fig. 24 is a plan view of the cylinder gears, the large driving gear therefor, and the transfer gear.

Fig. 25 is a front view of the split gear on one of the impression cylinders.

Fig. 26 is a vertical sectional view of the same, taken substantially on the line 26—26 of Fig. 25.

In the drawings, side members of the press frame are shown at 30. Cross frame members 31 join the side members at intervals, one of such

cross members being illustrated in Fig. 5. A bed 32 is mounted for reciprocation longitudinally of the frame, being arranged to run upon rollers 33. First color impression cylinder 34 and second color impression cylinder 35 are arranged above the bed, and are adapted to be raised and lowered for clearing or engaging the forms on the bed, as is usual in presses of this type. A transfer cylinder 36 is interposed between the cylinders 34 and 35, being of a diameter nominally one-half that of the impression cylinders.

According to the present invention the impression cylinders 34 and 35 rise and fall in directions approximately parallel to the planes of tangency between these cylinders and the transfer cylinder 36, but the gears 37 and 38 for the impression cylinders revolve upon fixed axes, and a relative movement between the impression cylinders and their gears, while maintaining the driving relation unimpaired, is permitted by Oldham couplings, to be described hereinafter. The gears 37 and 38 are therefore in constant complete mesh with their driving gear 39, which is a gear carried upon the periphery of a large driving wheel 40 mounted upon a shaft 41 which has suitable bearings in the frame of the press. The gear 39 also meshes with a gear 42 which is keyed to a shaft 43 that has bearing in the frame. On the same hub with gear 42 there is a further gear 44 with teeth of relatively coarse pitch, with which meshes a pinion 45 carried upon a short shaft 46, on the outer extremity of which is a belt pulley 47. The shaft 46 therefore is the power shaft, and it will be appreciated that power may be applied to it from any convenient source and in any convenient way.

The bed motion

While the bed motion per se of the press herein illustrated is covered in a separate application, Serial No. 754,837, filed by me of even date herewith, it is of importance in some of the aspects of the present invention, and it will therefore be described. The bed 32 has secured to its under surface a bed rack 48, with which a pinion 49 meshes continuously. The teeth of this rack and pinion are of comparatively fine pitch and are cut and finished with a high degree of accuracy. The pinion 49 is keyed to a shaft 50 which extends forward through the frame, as viewed in Fig. 2, and carries on its forward extremity a pair of pinions 51 and 52. The pinion 51 is adapted to mesh, at the proper time during a revolution of wheel 40, with an internal gear segment 53 secured to the wheel 40, while an external gear segment 54, also secured to the wheel 40, is adapted to mesh with pinion 52. Since the segment 53 engages with the outer side of pinion 51 and the segment 54 engages with the inner side of pinion 52, rotation is imparted to shaft 50 in opposite directions. The segments 53 and 54 are arranged diametrically opposite each other, and each segment extends through substantially 120° of arc, there being angles of 60° between the ends of the segments on opposite sides of the wheel. The teeth of segments 53 and 54 and the teeth of pinions 51 and 52 are of relatively fine pitch, and the gear ratios are such that a given angular displacement of wheel 40 in either direction produces the same length of travel of bed 32. Hence the mechanism provides constant speed travel for the bed in one direction during one-third of a revolution of wheel 40, constant speed travel for the bed in the other direction during another one-third of a revolution, and leaves two periods of

one-sixth of a revolution each for reversing the bed motion at the ends of its travel.

The reversing mechanism is geared directly to the constant speed mechanism through the meshing gears 39 and 42, the shaft 43 being the crank shaft which provides the simple harmonic motion for decelerating, stopping and accelerating in the opposite direction at each end of the bed stroke. On its inner extremity therefore this shaft carries a crank disc 55 upon which is mounted a 10 crank pin 56 which carries a roller 57. The axis of roller 57 is spaced radially from the center of disc 55 a distance equal to the pitch radius of gear 42 and the pitch diameter of gear 42 is one-third that of gear 39. Accordingly, one-half of a revolution of roller 57 corresponds in length of time with the movement past a given point of one of the 60° spaces between the segments on wheel 40.

The roller 57 runs in a vertical channel guide 58, which forms a part of a yoke 59 that slides 20 upon a guide bar 60 carried by the frame. The yoke 59 of this scotch yoke mechanism therefore makes three complete reciprocations to each revolution of wheel 40. There is secured to one end of the yoke 59 a rack 61 having teeth of relatively 25 coarse pitch which mesh with the teeth of a gear 62 that is keyed to a shaft 63, rotatably mounted in the frame of the press, preferably directly above shaft 41. This gear 62 is adapted to mesh with one or the other of a pair of aligned racks 64 30 and 65, which are spaced apart a distance approximating the length of travel of the bed, and are secured to the under surface of the bed. All of the gear elements employed in connection with the reversing mechanism, that is from the power 35 shaft 46 through to the racks 64 or 65, have relatively coarse pitch teeth, which are essential in order to absorb the heavy loads put upon them by the force needed to overcome the inertia of the bed.

A more detailed description of the bed motion and its operation will be found in my copending application previously referred to. It will therefore be sufficient to describe the operation here very briefly. Assuming that the parts are in the 45 position illustrated in Figs. 1 and 2, and that the direction of rotation of wheel 40 is that indicated by the arrow in Fig. 1, the bed is then at the limit of its travel to the right. Rotation of the crank roller 57 through the next 90° will move the rack 50 50 61 toward the right at an accelerating speed, which will produce an anti-clockwise rotation of gear 62, by means of which travel of the bed toward the left is begun. When the rack 64 is just ready to leave the gear 62, the segment 53 55 begins to engage the pinion 51, when constant speed rotation of shaft 50 in the anti-clockwise direction begins and constant speed travel is imparted to the bed in a direction toward the left. This continues through the next 120° of arc of 60 the wheel 40, when the segment 53 leaves the pinion 51 and gear 62 begins to mesh with rack 65. During the engagement between segment 53 and pinion 51 the gear 42 made a complete revolution, the crank roller 57 again arriving at its 65 uppermost position. The yoke 59 is then traveling at maximum speed, which is the same as the speed of the bed at that time, although in the opposite direction. The crank roller 57 now revolves clockwise 90°, slowing the yoke travel down to 70 zero, and thereby slowing down the bed travel correspondingly through the intermediacy of rack 61, gear 62 and rack 65. The next 90° of rotation of crank disc 55 begins the travel of yoke 59 toward the left, which produces travel of rack 65 75

and bed 32 toward the right, thereby beginning the travel of the latter in that direction and gradually accelerating it to the speed at which it moves in its constant speed travel. During the reversal of bed travel the rotation of shaft 56, which is then idle, is also reversed by virtue of the constant engagement of pinion 48 with rack 48. The segment 54 now comes into mesh with pinion 50 on the inner side of the latter, and clockwise rotation is imparted to shaft 50 at constant speed, thereby causing the bed to travel toward the right at constant speed. Again the crank disc 55 makes a complete revolution without effect upon the bed movement, that is in the interim between engagement of gear 62 with rack 65 and its engagement with rack 64. When the constant speed travel in this direction is completed, the segment 54 leaves its pinion 52, and the gear 62 again comes into engagement with rack 64. The crank roller 57 is then in its lowermost position. It turns clockwise 90° back to the position indicated in Fig. 1, causing the yoke 58 to move toward the left and gradually decelerating the motion of the bed in its travel toward the right until zero speed is reached, thereby completing the cycle.

Drive for impression and transfer cylinders

The gearing for the impression and transfer cylinders forms a closed circuit, that is to say the impression cylinder gears 37 and 38 are both in mesh with driving gear 39 on one side, and are both in mesh with the transfer cylinder gear 66 on the other side. In order that this closed circuit train of gears may run smoothly and accurately I include in the train adjustment means and means for taking up back lash. Gear 38 is a single piece gear meshing with gear 39. Gear 37 however is a split gear made up of two pieces 37a and 37b, illustrated somewhat in detail in Figs. 25 and 26. The gear piece 37a meshes with gear 39, and gear piece 37b meshes with the transfer cylinder gear, which is indicated generally by the reference number 66. The gear piece 37b is a ring which is L-shape in cross section and mounted to have a slight angular adjustment upon an annular ledge 67 forming a part of the gear piece 37a. The hub 68 of the gear is also a part of the gear piece 37a. These two gear pieces may be held in the desired position of adjustment by studs 69 mounted in the gear piece 37a and extending through slots 70 in gear piece 37b.

The transfer cylinder gear 66 is also a split gear, having two gear pieces 66a and 66b (Fig. 6) which are relatively adjustable. One of these pieces is keyed to the shaft of transfer cylinder 36, and the other is free to turn upon the shaft to a slight extent, coil spring 71 tending to maintain the gear pieces in an angularly displaced condition, whereby back lash is absorbed. Both of these gear pieces 66a and 66b mesh with the gear 38 and with the gear piece 37b. In addition to the fact that gear 66 is thus made in two pieces for absorbing back lash, the gear is also mounted so as to be slightly eccentric to the axis of rotation of cylinder 36. The extent of the eccentricity is but a few thousandths of an inch and is scarcely apparent to the eye, but for the sake of illustration it has been exaggerated in Fig. 23, where the point 72 represents the center of rotation of the gear and of the cylinder 36 upon which it is mounted, while the point 73 represents the center of the circle of the gear. Both of the gear pieces 66a and 66b are thus eccentric-

cally mounted. It will be observed that when the parts are in the position of Fig. 23 the teeth of the gear at its high point are in close mesh with gear 38, while the teeth which are in mesh with gear 37 at the same time are nearly opposite to the high point of gear 66 and therefore near to the low point of the gear. Hence there is a close meshing between gears 38 and 66 and a loose meshing between gears 37 and 66, and gear 66 takes its drive from gear 38. The sheet grippers 74 for transfer cylinder 36 are arranged approximately in line with the high point of eccentricity of the gear. Assuming that a transfer of a sheet from grippers 74 to grippers 75 on cylinder 35 is being made at the instant illustrated in Fig. 23, it will be apparent that very accurate positioning of the sheet at that time is effected. In a similar way, when a sheet is being taken from cylinder 34 by transfer cylinder 36, the grippers 74 and the high part of gear 66 will be adjacent the cylinder 20 34 and the gear 37, and at that time gear 66 will be in close mesh with gear 37. Hence the gear 66 is driven by the first color cylinder gear 37 when receiving a sheet from the first color cylinder, and by the second color cylinder gear 38 when transferring the sheet to the second color cylinder. The eccentric arrangement also produces a gradual transfer of the drive from one gear to the other, thereby insuring quiet running and reducing wear.

The shafts 76 and 77 are eccentrically mounted in bearing sleeves 78 and 79 respectively, which are oscillatably mounted in bearings in the opposite side frame members of the press. Hollow outboard bearings 80 are attached to the forward frame member. Upon these bearings the hub 68 of gear 37 and the hub 81 of gear 38 rotate. These gears therefore turn upon fixed axes.

The Oldham couplings for gears 37 and 38 are identical, and accordingly that for gear 38 only will be described. A sleeve 82 is keyed to the extremity of shaft 77 within the hollow bearing 83. Clearance is maintained between the bearing and the sleeve at all times. On its outer end the sleeve 82 carries a plate 83 which is adjustably secured by means of bolts and slots 84 and 85 to a driven plate 85. The latter carries at diametrically opposite points two anti-friction rollers 87 that extend into slots 88 in a floating disc 89, these slots being located 180° apart. At points 50 located along a diameter arranged at 90° to the diameter through slots 88 there are two other slots 90 in the floating disc which accommodate two rollers 91 that are mounted in the gear 38. The rollers 91 are also connected by pins 92 and coil springs 93 with perforated bosses 94 upon the driven plate, which latter arrangement has no effect other than as a slack take-up, or means for keeping the rollers 87 or 91, as the case may be, in contact always with the same sides of their 60 slots. The drive from the gear 38 takes place by way of rollers 91 fastened to the gear which extend into the slots 90 of the floating plate 89. When the impression cylinder 35 is up, as it is in Fig. 1, and the parts are otherwise in the position 65 of Fig. 1, the rollers 91 will be displaced from the central positions of their slots, but they will however communicate a given angular rotation of the gear to the floating plate 89 without any change in the angular extent of the rotation. The floating plate 89 will in turn communicate the same angular rotation to the rollers 87 carried by the driven plate 86 on the forward extremity of shaft 77. Thus, the slot and roller connections 70 serve to drive the cylinder 35 at the same rate 75

as the gear 38, in spite of the fact that the axes of rotation of the gear and cylinder are displaced to some extent.

It will be observed that, by means of the gearing arrangement described, the two impression cylinders receive their driving power from the gear 39 with which their gears 37 and 38 are constantly in full mesh. Their relation is therefore as close as it is possible to make it, and as these gears are all mounted to turn upon fixed axes, they may be built to have close and accurate meshing relationship. Furthermore, inasmuch as the constant speed drive for the bed is taken directly from the driving wheel 40, which turns the impression cylinders, the operative relationship between the cylinders and the bed is also close and accurate, thereby assisting materially in maintaining accurate register.

20

Impression cylinder movements

The bearing sleeves 78 and 79 for the impression cylinder shafts extend outwardly beyond the frame side members, where they are enlarged to form rockers 95 and 96 respectively. The movement of these rockers in one direction is limited by stops 97 which are adapted to engage adjustable stops 98 on the rockers. When the stops 97 and 98 are in engagement the cylinders are in their lowered or printing position. Their movement in the upward direction is limited by other stops to be described hereinafter.

The rockers 95 and 96 are connected by means of adjustable links 99 and 100 respectively with levers 101 and 102 that are mounted for pivotal movement about shafts or pivots 103 and 104, the levers 101 and 102 being connected in turn by links 105 and 106 with cranks 107 and 108 keyed to rock shafts 109 and 110 respectively. This lever and link mechanism between the rockers 95 and 96 on the one hand and the rock shafts 109 and 110 on the other hand is located on the outer side of the frame side members 30, as will be apparent from Fig. 4. When the parts are in the positions shown in Figs. 3, 8 and 16 the impression cylinders are both in their raised positions. When the cranks 107 and 108 are swung toward each other into the positions indicated by dotted lines in Fig. 3, the pivot points 111 and 112 will be raised to the dotted line positions of that figure, lowering the shafts 76 and 77 and the impression cylinders carried thereby, in order to bring the cylinders to such a level that they may cooperate with the first and second color forms 113 and 114 carried by the bed of the press. When the cylinders 34 and 35 are down in printing position the passage of the form thereunder places a considerable upward pressure upon their mountings. The links and levers of my cylinder mechanism are so designed and arranged however that when the cylinders are lowered to printing position the links 99 and 100 are in substantial alignment with the pivots 103 and 104, as indicated in dotted lines. Hence any upward strain on the cylinders is delivered through the links 99 and 100 directly to the pivots 103 and 104, which are rigidly supported in the frame. Furthermore, when the cylinders are up, the links 105 and 106 are in substantial alignment with the levers 107 and 108 respectively. Hence the weight of the cylinders themselves acts to hold them in the up position. It will be observed therefore that 75 in this construction there are in effect two tog-

gles, one consisting of the link 100 and that part of lever 102 which is above or to the right of the pivot 104, and the other consisting of the link 106 and the crank 108.

The rock shafts 109 and 110 are provided with cranks 115 and 116, by means of which the shafts are oscillated so as to move the cranks 107 and 108 from the full line position of Fig. 3 to the dotted line position and back again once for each cycle of the bed, that is to say the mechanism maintains the impression cylinders in their raised positions at all times except while the corresponding color forms are traveling beneath the cylinders on the printing stroke of the bed. Fig. 18 illustrates the beginning of the printing operation, when color form 113 is just beginning its travel beneath the impression cylinder 34. As soon as color form 114 begins to travel beneath cylinder 35 the printing of another sheet in the second color will begin. The raising of the cylinders begins after the printing is completed and before the bed reaches the end of its travel on the printing stroke.

The operating cranks 115 and 116 are swung back and forth by reciprocating bars 117 and 118. The crank 115 is provided with a crank pin 119 which extends through a slot 120 formed in the end of the bar. The pin 119 is normally latched to the inner end of the slot by a latch bar 121 which is pivoted upon the pin 119 and provided with a shoulder or hook that engages over a square pin 122 projecting from the side of the bar 117. Gravity tends to maintain the latch 121 in latching position, as illustrated in Fig. 16. It will be apparent that when the latch 121 is in the operative position there illustrated, the connection between the bar 117 and the crank pin 119 is in effect a simple pivotal connection, and movement of the bar 117 in either direction is communicated to the crank 115. However, when the latch 121 is raised, movement of bar 117 to the left for the length of the slot 120 has no effect upon the crank 115, and the reciprocation of the bar 117 therefore no longer serves to raise and lower the cylinder 34.

The connection between the reciprocating bar 118 and crank 116 is similar to that above described between the bar 117 and crank 115, comprising a crank pin 123 extending through a slot 124 in the bar 118, and having a latch bar 124 pivoted thereto, the latter bar having a shoulder portion or hook which engages a squared pin 125 mounted in the end of bar 118. Such differences as exist between the two sets of parts are due to the fact that cranks 115 and 116 move in opposite directions.

The bars 117 and 118 receive their motion of reciprocation preferably from box cams 126 and 127, which are keyed to a cam shaft 128. The latter is driven by means of a gear 129 which meshes with a pinion 130 on shaft 43. The gearing is such that cam shaft 128 makes one revolution for each revolution of the wheel 40 and each complete reciprocation of the bed 32.

Cams 126 and 127 have cam grooves 131 and 132 therein, within which run roller followers 133 and 134 that are mounted upon arms 135 and 136 pivotally hung at their upper ends upon portions of the machine frame. These arms at their lower ends are pivotally connected with the bars 117 and 118 respectively. Obviously, therefore, as the cams 126 and 127 turn through one revolution the arms 135 and 136 swing back and forth once and produce one complete reciprocation of the bars 117 and 118, which produces one up and 75

down movement of the impression cylinders in the regular normal operation of the machine in printing two colors.

Disabling either impression cylinder

At times it is desirable to use the press for printing in one color only. At other times it may be desirable to inspect the work done in one color only while the press is operating upon a two-color job, and to do this by temporarily holding one of the impression cylinders in raised position. It is a part of my invention to provide mechanism for accomplishing these results and this mechanism will now be described.

On the cam shaft 128 I mount two further cams 137 and 138 having peripheral cam surfaces, the cam 137 being considerably wider than the cam 138 for a purpose which will presently appear. The preferred contours of these cams are illustrated in detail in Figs. 21 and 22, where the dot and dash circles are included to assist the eye in determining the relative heights of different portions of the cams.

139 is a rod which is mounted in a bracket carried by the machine frame. Upon this rod are pivotally mounted two similar V-shaped levers 140 and 141 having roller followers 142 and 143 respectively, which are adapted to run over the periphery of cams 137 and 138. To the lower arms of levers 140 and 141 are connected pull rods 144 and 145 that are urged toward the right by coil springs 146 and 147 respectively, thereby tending to hold the followers in contact with their cams. 148 is a shaft mounted in the frame of the press. It serves as a pivotal mounting for two oscillatable cams 149 and 150 which have hubs surrounding the shaft. From these hubs extend cranks 151 and 152 that are connected by pivot pins with the rods 144 and 145. Hence, when the rods 144 and 145 move toward the right from the position illustrated in Fig. 17, the cams 149 and 150 swing upwardly from the positions in which they are shown in that figure. These cams are so positioned as to engage beneath rollers 153 and 154 on latch levers 121 and 124', and to raise said rollers when the cams are actuated by the rods 144 and 145.

If the rollers 142 and 143 were permitted to follow their cams at all times, the cams 149 and 150 would be raised once for each reciprocation of the bed, thereby throwing the latch bars 121 and 124' out of latching position at the proper time to enable bars 117 and 118 to reciprocate without moving cranks 115 and 116. Means are provided however to normally prevent the rollers 142 and 143 from following their cams. To this end levers 140 and 141 are provided with arms having at the ends thereof hooks 155 and 156, which are normally engaged by hooks 157 and 158 on hook members 159 and 160. These hook members are pivotally mounted upon a rod 161 supported in the same bracket which supports rod 139. The pivotal points for these two hook members 159 and 160 are such that gravity gives them a bias toward hooking position. When the hooks are engaged, as indicated in Fig. 17, the levers 140 and 141 are hooked back to such an extent that they are not moved by any portions of the surfaces of cams 137 and 138 except the short high spots h and h' respectively. (See particularly Figs. 21 and 22.) Hence for each revolution of the cam shaft 128 the levers 140 and 141 receive a slight swing clockwise, not enough to raise rollers 153 and 154, but sufficient to disengage hooks 155, 157 or 156, 158 if any force is

present tending to swing hook member 159 or 160 clockwise. Ordinarily there is no such force present, and gravity holds hooks 157 and 158 in position to be again engaged by hooks 155 and 156 as soon as the high spots of the cams pass beyond 5 rollers 142 and 143.

I provide manually controlled means however for exerting such a pressure upon either one of the hook members 159 or 160, thereby permitting unhooking of the lever 140 or 141 when the high 10 spot of the corresponding cam produces the slight shift of the lever toward the right, as previously described. Each of the hook members is provided with a horizontally extending arm 161' or 162, in which is mounted a pin 163 or 164 extending 15 through an elongated slot in the lower extremity of vertical members 165 or 166, which are identical except as to length. At the upper end of each of these vertical members there is a vertical slot 167 which receives a pin 168 that extends also 20 through the head 169 of a guide rod 170 and through a hole in a crank 171. A set screw 172 holds the pin 168 in the crank. The guide rod 170 is surrounded by a coil spring 172' which bears at its lower end against a block 173 having 25 a hole therethrough in which the rod 170 is guided. The block 173 is provided with a threaded post 174 which extends through a hole in the bar 165 or 166, as the case may be, and receives a nut 175 by means of which the block is held in 30 place. A rock shaft 176 is mounted in bearings in the frame and extends outside of the frame, where it is provided with a hand crank 177. Its inner end extends into a hole in the crank 171, to which it is keyed. It may be held from withdrawal by a set screw 178.

We will now assume that the operator desires to interrupt momentarily the printing of the second color. He then turns crank handle 177 on vertical bar 166 from a position corresponding to 40 the full line or "on" position of Fig. 14 through 180° to the dotted line or "off" position of that figure, which corresponds to the full line position of Fig. 11. The first effect of this hand crank movement is to depress the bar 166 sufficiently 45 to cause the slot in its lower end to engage the pin 164. The next effect is to store up energy in the spring 172', which occurs for the reason that pin 168 is swung around and down to a level below that of shaft 176. Force is therefore exerted by 50 the spring 172' through the block 173 tending to depress bar 166 further. This energy is not permitted to swing hook member 160 clockwise at once because of the engagement between hooks 156 and 158. As soon as high spot h' of cam 55 138 tips lever 141 clockwise slightly, the hooks 156 and 158 disengage, and the spring pressure exerted upon the bar 166 throws up the hook member to the position shown in Fig. 12. Its motion in this direction is limited by stop pin 180. 60 In Fig. 12 the roller follower 143 is running upon the portion i' of cam 138, which maintains the lever 141 in position substantially the same as when it is hooked up. As soon as the low part, i' 65 of the cam encounters the roller follower 143 however, as shown in Fig. 13, the lever 141 is swung by the spring 147 and the rod 145 to the position indicated in the latter figure, which throws cam 138 up to the position of Fig. 13 and disconnects the latch bar 124' from square pin 70 125. This occurs at a time when the reciprocating bar 118 is at the left end of its travel and the cylinder is raised. As the bar 118 moves toward the right the square pin 125 moves beneath the latch 124' without communicating any pull 75

- to the latch, so that the slot 124 travels over the pin 123 and fails to swing crank 116 to the right. The cylinder is therefore left in its elevated position. This same condition prevails upon each bed stroke so long as the lever 141 remains unhooked.
- Now, assuming that the operator desires to resume the printing of the sheet in the second color, he swings lever 177 back to the full line position of Fig. 14, thereby relieving the spring pressure upon pin 164. The hook member 160 then tends to fall by gravity back to the position of Fig. 11. It will first engage upon the top of hook 156 however; where it will rest until high spot h' of cam 138 again passes beneath roller 143, which will 15 shift hook 156 far enough to permit hook 158 to fall into hooking position. Thereafter the rotation of cam 138 will not affect the latch bar 124', and the up and down movement of the cylinder will be resumed.
- 20 The up and down movement of the first color impression cylinder may be disabled or interrupted in the same manner by the depression of vertical bar 165, which has its own crank handle at a higher level than that of bar 166, as shown in Fig. 3. However the mechanism and method of control are practically identical with that above described, and consequently no separate statement with respect to operation is necessary.
- 25 30 *Raising or lowering both impression cylinders in sequence*
- Means are provided for interrupting the printing of both colors in sequence, and this means 35 may be actuated either manually or automatically. The mechanism for this purpose is so constructed as to hold the first color impression cylinder raised at the end of one printing stroke and to hold the second color impression cylinder 40 raised at the end of the next succeeding stroke, in order that the last sheet printed in the first color will be completed, that is printed in the second color, before the operation is entirely stopped.
- The control for this mechanism comprises a 45 vertically movable rod 181 (Fig. 3) to which is connected a spring 182 that tends to pull the rod down. Means of suitable character is provided to latch the rod 181 in its elevated position, which position corresponds to the normal running position of the press. Such means may be manually 50 or automatically controlled, preferably either one. The automatic control may be tripped by the failure of a sheet to come through the sheet feeding means (not shown) employed in connection with the press. The present invention is not concerned with the detail of any such tripping means, and hence none is illustrated. However, I have indicated diagrammatically in Fig. 3 a projecting arm 183 extending outwardly from 55 the rod 181, supported by a trigger 184 pivoted at 185 to any convenient support, and provided with an operating arm 186. Any convenient automatic means may be used to depress arm 186 and release the trigger, or it may be depressed 60 manually. The rod 181 is pivotally attached to a crank 187 keyed to a shaft 188. A crank 189 keyed to the opposite end of shaft 188 is pivotally connected with a longitudinally movable rod 190. The opposite end of rod 190 is provided 65 with a slot 191 which receives a pin 192 upon a downwardly extending portion of a hook member 193, pivotally mounted upon rod 181 between the hook members 159 and 160. The hook member 193 is provided with a hook 194 which normally 70 engages a hook 195 upon an arm of a lever

196 which is pivotally mounted upon rod 139 between levers 140 and 141. The lever 196 carries a roller follower 197 that is adapted to run upon wide cam 137 alongside roller 142, as shown in Figs. 4 and 8. Lever 196 is somewhat different from levers 140 and 141, being provided with an extra arm 198 which carries in its extremity a pin 199 that extends beneath hook member 160 but does not normally contact with that member. Hook member 193 carries a pin 200 which extends beneath hook member 159. The length of pins 199 and 200 is of course greatly exaggerated in the diagrammatic view of Fig. 17, the levers and hook members of the disabling mechanism being positioned close together in the apparatus as 15 built, and as disclosed in the plan views of the drawings. Lever 196 is maintained under spring pressure tending to cause roller 197 to ride upon its cam. This is provided by a rod 201 which is pivotally connected with the lower end of lever 20 196 and is urged toward the right by a coil spring 202. The arm 203, pivotally connected with rod 201 and oscillatable upon shaft 148, is provided merely as a guide and support for the rod.

Now, in case the rod 181 is unlatched, either 25 manually or automatically, and spring 182 is thereby permitted to exert pressure upon rod 190 tending to shift that rod to the left, the end of slot 191 will engage pin 192 and will exert pressure tending to disengage hooks 194 and 195. 30 Such disengagement will not occur however until high spot h' of cam 137 passes beneath roller 197. When this happens, hook member 193 is swung up, and by reason of the pin 200 it carries up with it hook member 159, which is permitted to 35 rise because of the disengagement of hooks 155 and 157 simultaneously with the disengagement of hooks 194 and 195, the rollers 142 and 197 passing over the same high spot h' . The release 40 of lever 140 permits cam 149 to swing up in response to the action of spring 146, and thereby disable the first color impression cylinder. As soon as roller 197 is engaged by the level l of cam 137, pin 199 engages the under side of hook member 160 without putting pressure upon it. But 45 when the roller 197 rides down upon the level l of the cam, the pin 199 puts upward pressure on the hook member 160. During the time that this upward pressure is effective the high spot h' of cam 138 passes under roller 143 of lever 141 50 and disengages hooks 156 and 158, whereupon the hook member 160 swings up out of hooking position. The lever 141 does not immediately swing to raise cam 150, because its follower 143 rides upon the level l' of cam 138 for about half 55 of a revolution before the low level l' permits cam 150 to be raised and the latch arm 124' to be swung up. The slots at the lower ends of vertical bars 165 and 166 permit the movement of hook members 159 and 160 in this sequence control 60 operation.

It will be observed therefore that from the time roller 142 rides onto the portion l of cam 137, disabling the mechanism for accomplishing the up and down movement of the first color impression cylinder, the cam shaft makes almost one-half of a revolution before high spot h' of cam 138 unhooks hook member 160, and that from that time until the low level l' of cam 138 70 passes under roller 143 to disable the second color impression cylinder approximately another half revolution of the cam shaft takes place. Hence the disabling of the second color impression cylinder occurs approximately a full revolution or 75

a full bed cycle later than the disabling of the first color impression cylinder.

Both impression cylinders being thus held in raised position, no printing takes place in either color. Now, when it is desired to resume printing, the rod 181 is raised and the trigger 184 or its equivalent put into the latching position illustrated in Fig. 3. The spring pressure upon rod 190 is thereby relieved, and the hook member 193 tends to return by gravity to its normal latching position. At the same time it permits hook member 159 to return by gravity to a like extent.

Now, as soon as the high spot of cam 137 again passes beneath rollers 142 and 187 the two levers 140 and 196 are hooked up. The hooking up of lever 196 relieves the upward pressure of pin 199 upon hook member 160, and when high spot h' of cam 138 next passes beneath roller 143 the lever 141 is hooked up. This does not however occur until the first printing stroke of the bed following the lowering of the first color cylinder has been completed. In other words the mechanism sets itself directly after the first printing stroke is completed, so as not to interfere thereafter with the regular up and down movement of the second color impression cylinder. In this way the lowering of the second color cylinder prior to the feeding of a sheet thereover is avoided.

The sequence control of the impression cylinders is essential only when an interruption in the feed of sheets takes place, either accidentally or intentionally. When the feed of sheets is continuous either cylinder singly may be held in raised position, and lowered again at will by means of the manual control means previously described.

Adjustable stops for limiting the turning of cranks 115 and 116 in the cylinder raising direction are illustrated at 204 and 205 respectively in Figs. 7 and 8.

In the foregoing description I have necessarily gone somewhat into detail in order to explain fully the particular embodiments of the invention herein illustrated, but I desire it to be understood that such detailed disclosures are not to be construed as amounting to limitations, except as they may be included in the appended claims.

Having thus described my invention, I claim:

1. In a printing press, a reciprocating bed, two impression cylinders cooperating with said bed, gears on said impression cylinders, a rotating element turning on a fixed axis having a gear meshing with the gears on both of said impression cylinders, and means mounted on a single shaft actuated directly by said rotating element for imparting constant speed motion to said bed on the printing stroke.

2. In a printing press, a reciprocating bed having end reversal movements and intermediate constant speed travel, two impression cylinders cooperating with said bed, gears on said impression cylinders, a driving wheel with a fixed axis having a gear meshing with the gears on both of said impression cylinders, and means for reciprocating said bed during its constant speed travel comprising gear elements fixed with respect to said driving wheel, and a single shaft actuated directly by said gear elements.

3. In a printing press, a reciprocating bed having end reversal movements and intermediate constant speed travel, two impression cylinders cooperating with said bed, gears for said impres-

sion cylinders, Oldham couplings between said impression cylinders and the gears therefor, a driving wheel with a fixed axis having a gear meshing with both of the gears for said impression cylinders, and means mounted on a single shaft actuated directly by said driving wheel for reciprocating said bed during its constant speed travel.

4. In a printing press, a reciprocating bed, two impression cylinders cooperating with said bed, gears on said impression cylinders, a driving wheel with a fixed axis having a gear meshing with the gears on both of said impression cylinders, a bed rack, a driving pinion therefor, and means for rotating said pinion at constant speed in opposite directions at spaced intervals, comprising gear elements rotating with said driving wheel and angularly spaced from each other.

5. In a printing press, a reciprocating bed, two impression cylinders cooperating with said bed, gears on said impression cylinders, a driving wheel with a fixed axis having a gear meshing with the gears on both of said impression cylinders, a bed rack, a driving pinion therefor, means for rotating said pinion at constant speed in opposite directions at spaced intervals, comprising angularly spaced gear elements rotating with said driving wheel, and cylinder throw-off means adapted to act upon said cylinders one at a time.

6. In a printing press, a reciprocating bed, two impression cylinders cooperating with said bed, gears for each of said cylinders mounted to turn upon fixed axes, Oldham couplings between said gears and said cylinders, means for raising and lowering said cylinders during the operation of the press, and a driving wheel having a gear meshing with both of said impression cylinder gears.

7. In a printing press, a reciprocating bed, two impression cylinders cooperating with said bed, gears for each of said cylinders mounted to turn upon fixed axes encircled by said cylinders, means for causing relative movement between said bed and cylinders toward and away from each other while maintaining a constant speed driving relation between said gears and impression cylinders, and a driving wheel having a gear meshing with both of said impression cylinder gears.

8. In a printing press, a reciprocating bed, two impression cylinders cooperating with said bed, gears for each of said cylinders mounted to turn upon fixed axes encircled by said cylinders, means for causing relative movement between said bed and cylinders toward and away from each other while maintaining a constant speed driving relation between said gears and impression cylinders, a driving wheel with a fixed axis having a gear meshing with both of said impression cylinder gears, and means for reciprocating said bed comprising gear sectors fixed for rotation with said drive wheel and including a single shaft directly actuated by said sectors.

9. In a printing press, a reciprocating bed, two impression cylinders cooperating with said bed, gears for each of said cylinders mounted to turn upon fixed axes encircled by said cylinders, means permitting relative movement between said bed and each of said cylinders toward and away from each other while maintaining a constant speed driving relation between said gears and impression cylinders, means for raising and lowering said cylinders during the operation of the press, and a driving wheel having a gear with a pitch diameter twice that of the impression cylinder.

- gears and meshing with both of said impression cylinder gears.
10. In a printing press, a reciprocating bed, two impression cylinders cooperating with said bed, 5 gears for each of said cylinders mounted to turn upon fixed axes encircled by said cylinders, means permitting relative movement between said bed and each of said cylinders toward and away from each other while maintaining the driving relation between said gears and impression cylinders, means for raising and lowering said cylinders during the operation of the press, a driving wheel with a fixed axis having a gear with a pitch diameter twice that of the impression cylinder 10 gears and meshing with both of said impression cylinder gears, and means for imparting constant speed movement to said bed on the printing stroke comprising a single shaft driven directly from said driving wheel.
20. 11. In a printing press, a reciprocating bed, two impression cylinders cooperating with said bed, gears for each of said cylinders mounted to turn upon fixed axes encircled by said cylinders, means permitting relative movement between 15 said bed and each of said cylinders toward and away from each other while maintaining the driving relation between said gears and impression cylinders, means for raising and lowering said cylinders during the operation of the press, a driving wheel with a fixed axis having a gear meshing with both of said impression cylinder 20 gears, a bed rack, a driving pinion thereon, and means for rotating said driving pinion at constant speed in opposite directions at spaced intervals, comprising angularly spaced gear segments 25 rotating with said driving wheel.
12. In a printing press, a printing cylinder and a transfer cylinder, intermeshing gears on said cylinders, said transfer cylinder gear having a 30 portion of its teeth extending further from the axis of rotation of its cylinder than other portions thereof.
13. In a printing press, two impression cylinders, four gears forming an operative system, 35 said system comprising a first gear for driving said system, a second gear on one of said cylinders meshing with the first gear, a third gear on the other of said cylinders meshing with the first gear, and a fourth gear in driven relation 40 only with respect to each of the second and third gears of said system.
14. In a printing press, two impression cylinders, four gears forming an operative system, 45 said system comprising a first gear for driving said system, a second gear on one of said cylinders meshing with the first gear, a third gear on the other of said cylinders meshing with the first gear, and a fourth gear in driven relation 50 only with respect to each of the second and third gears of said system.
15. In a printing press, two printing cylinders, a transfer cylinder interposed between the printing cylinders, gears on said printing cylinders, 55 and a gear on said transfer cylinder meshing with both of the printing cylinder gears, said transfer cylinder gear having a portion of its teeth extending further from the axis of rotation of the transfer cylinder than the other portions thereof.
70. 16. In a printing press, two printing cylinders, a transfer cylinder interposed between the printing cylinders, gears on said printing cylinders, 60 a gear on said transfer cylinder meshing with both of the printing cylinder gears, said transfer cylinder gear having a portion of its teeth 65
- extending further from the axis of rotation of the transfer cylinder than the other portions thereof, and sheet grippers on said transfer cylinder positioned substantially in a line with the high teeth of the transfer cylinder gear. 5
17. In a printing press, a printing cylinder and a transfer cylinder, intermeshing gears on said cylinders, said transfer cylinder gear being positioned slightly eccentric to the axis of rotation of its cylinder. 10
18. In a printing press, two printing cylinders, a transfer cylinder interposed between the printing cylinders, gears on said printing cylinders, 15 and a gear on said transfer cylinder meshing with both of the printing cylinder gears, said transfer cylinder gear being positioned slightly eccentric to the axis of rotation of the transfer cylinder. 15
19. In a printing press, two printing cylinders, a transfer cylinder interposed between the printing cylinders, gears on said printing cylinders, 20 a gear on said transfer cylinder meshing with both of the printing cylinder gears, said transfer cylinder gear being positioned slightly eccentric to the axis of rotation of the transfer cylinder, and sheet grippers on said transfer cylinder positioned substantially in line with the high point of the gear circle. 25
20. In a printing press of the reciprocating bed type, a pair of impression cylinder members, a transfer cylinder member interposed between said impression cylinder members, a driving wheel member interposed between said impression cylinder members, and gearing for connecting said members in operative relation in a closed circuit, 30 said gearing comprising a gear for one of said members having two parts angularly adjustable with respect to each other, one of said parts meshing with a gear on the member next adjacent on one side and the other of said parts 35 meshing with the gear of the member next adjacent on the other side. 40
21. In a printing press of the reciprocating bed type, a pair of impression cylinders, gears for each of said cylinders, an intermediate gear meshing with both of said cylinder gears, an angularly adjustable gear carried by one of said cylinder gears, a transfer cylinder interposed 45 between said impression cylinders, and a transfer gear on said transfer cylinder meshing with said adjustable gear and the gear on the other cylinder. 50
22. In a printing press of the reciprocating bed type, a pair of impression cylinder members, a transfer cylinder member interposed between said impression cylinder members, a driving wheel member interposed between said impression cylinder members, gearing for connecting said members in operative relation in a closed circuit, 55 said gearing comprising a gear for one of said members having two parts angularly adjustable with respect to each other, one of said parts meshing with a gear on the member next adjacent on one side and the other of said parts meshing with the gear of the member next adjacent on the other side, and said last named gear carrying back lash take-up means. 60
23. In a printing press, two printing cylinders, a transfer cylinder interposed between the printing cylinders, gears on said printing cylinders, 70 and a gear on said transfer cylinder meshing with both of the printing cylinder gears, said transfer cylinder gear being positioned slightly eccentric to the axis of rotation of the transfer cylinder and carrying back lash take-up means. 75

24. In a printing press, two printing cylinders, a transfer cylinder interposed between the printing cylinders, gears on said printing cylinders, and a gear on said transfer cylinder meshing with both of the printing cylinder gears, said transfer cylinder gear being positioned slightly eccentric to the axis of rotation of the transfer cylinder and being formed in two parts with a resilient back lash take-up connection between them.
25. In a printing press of the reciprocating bed type, a pair of impression cylinders, a transfer cylinder interposed between said impression cylinders, gears for each of said impression cylinders, a driving wheel having a gear meshing with both of said impression cylinder gears, and a transfer cylinder gear meshing with said impression cylinder gears, said transfer cylinder gear comprising back lash take-up means.
26. In a two-color printing press of the reciprocating bed type, first and second color impression cylinders, mechanism timed with the bed movements for raising and lowering said cylinders, means for stopping or starting the up and down movement of the first and second color impression cylinders in successive bed cycles, and manually controlled means for stopping or starting the up and down movement of either cylinder singly during the operation of the press, said first named means being adapted to function upon one cylinder alone when the other cylinder is maintained in raised position by said manually controlled means.
27. In a printing press, an impression cylinder, means for raising and lowering the impression cylinder, a reciprocating bar, means for producing a reciprocation of the bar for each cycle of the press, an operative connection between said bar and said raising and lowering means, said connection being normally active for raising the cylinder when the bar moves in one direction and for lowering the cylinder when the bar moves in the opposite direction, and means separately controlled for disabling the connection when the bar moves in the cylinder lowering direction.
28. In a printing press of the reciprocating bed type, an impression cylinder, a cam shaft making one revolution for each reciprocation of the bed, means for raising and lowering the impression cylinder comprising an oscillating shaft, a reciprocating bar, means including a cam on the cam shaft for producing a complete reciprocation of the bar for each revolution of the cam shaft, said bar having a lost motion connection with the oscillating shaft, means normally operative for taking up the lost motion in said connection, and means for disabling said last named means, whereby the bar is permitted to reciprocate without moving said oscillating shaft.
29. In a printing press of the reciprocating bed type, an impression cylinder, means for raising and lowering said cylinder, a reciprocating bar, means for producing a reciprocation of the bar for each cycle of the bed, a pin and slot connection between said bar and the said raising and lowering means, means for normally latching the pin of said connection to one end of the slot, and means for disabling said latching means to permit reciprocation of the bar without actuation of said raising and lowering means.
30. In a printing press of the reciprocating bed type, an impression cylinder, means for raising and lowering said cylinder, a reciprocating bar, means for producing a reciprocation of the bar for each cycle of the bed, a pin and slot connection between said bar and the said raising and lowering means, means for normally latching the pin of said connection to one end of the slot, and means for disabling said latching means to permit reciprocation of the bar without actuation of said raising and lowering means.
31. In a printing press of the reciprocating bed type, two impression cylinders, means for raising and lowering said cylinders, a pair of reciprocating bars, means for producing a reciprocation of each of said bars for each cycle of the bed, a pin and slot connection between each of said bars and the raising and lowering means for one of said cylinders, means for normally latching the pin of each of said connections to one end of the slot, means adapted to function once during each bed movement cycle for disabling said latching means throughout a portion of the cycle, hook members for hooking up both of said disabling means to prevent their actuation, manually controlled means for operating one of said hook members, and further means for operating both of said hook members in successive cycles of the bed.
32. In a printing press of the reciprocating bed type, two impression cylinders, two reciprocating bars, means for reciprocating both bars once during each cycle of the bed, means for raising and lowering said impression cylinders comprising two rock shafts having cranks, a pin and slot connection between each of said bars and one of said cranks, means for normally latching the pin of each connection to one end of the slot thereof, and controllable means for disabling said latching means when the cranks reach the positions corresponding to the raised cylinder positions.
33. In a printing press of the reciprocating bed type, two impression cylinders, two reciprocating bars, means for reciprocating both bars once during each cycle of the bed, means for raising and lowering said impression cylinders comprising two rock shafts having cranks, a pin and slot connection between each of said bars and one of said cranks, means for normally latching the pin of each connection to one end of the slot thereof, and manually controlled means for disabling either one of said latching means when its crank reaches the position corresponding to the raised cylinder position.
34. In a printing press of the reciprocating bed type, two impression cylinders, two reciprocating bars, means for reciprocating both bars once during each cycle of the bed, means for raising and lowering said impression cylinders comprising two rock shafts having cranks, a pin and slot connection between each of said bars and one of said cranks, means for normally latching the pin of each connection to one end of the slot thereof, and controllable means for disabling said two latching means in sequence in successive cycles of the bed movement.
35. In a printing press, a cam shaft, cylinder raising and lowering mechanism, a cam on said shaft for operating said mechanism, means for disabling said mechanism comprising a second cam on said cam shaft and a lever having a follower running on said last named cam, and means for hooking up said lever to prevent actuation of the lever by the cam.
36. In a printing press, a cam shaft, cylinder

- raising and lowering mechanism, a cam on said shaft for operating said mechanism, means for disabling said mechanism comprising a second cam on said cam shaft and a lever having a 5 follower running on said last named cam, said lever also having a hook, a pivoted hook member having a hook adapted to engage the hook of said lever for holding the latter in inoperative position, said second cam having a high spot 10 adapted to swing the lever to a position to disengage said hooks, said hook member having a bias toward hooking position, and controllable means for applying pressure tending to withdraw said hook member from hooking position.
- 15 37. In a printing press, two impression cylinders, a cam shaft, mechanism for raising and lowering said cylinders, means driven by said shaft for operating said mechanism, means for disabling said mechanism comprising a pair of 20 cams on said cam shaft and a pair of levers each having followers running on said cams, means for hooking back each of said levers to prevent actuation thereof by their cams, and controllable means for setting said hooking back 25 means into operation in sequence in successive cycles of the press.
38. In a printing press, two impression cylinders, a cam shaft, mechanism for raising and lowering said cylinders, means driven by said 30 shaft for operating said mechanism, means for disabling said mechanism comprising a pair of cams on said cam shaft and a pair of levers each having followers running on said cams, each of said levers also having a hook, a pair of hook 35 members each having a hook adapted to engage the hook of one of said levers for holding the latter in inoperative position, each of said cams having a high spot adapted to swing the corresponding lever to a position to disengage said 40 hooks, said hook members having a bias toward hooking position, and mechanism controlled by said cam shaft for applying pressure tending to withdraw one of said hook members from hooking position and thereafter on the next cycle of 45 the press to apply pressure tending to withdraw the other of said hook members.
39. In a printing press, a printing cylinder, a gear for driving said cylinder mounted to turn on a fixed axis, driving connections between said gear 50 and said cylinder comprising an element rotatable with the cylinder extending loosely through the hub of said gear and carrying an element rotat- 55 ing in a plane substantially parallel with the plane of said gear and axially outward thereof, and operative connections between said last named element and said gear.
40. In a printing press, a printing cylinder, framing for supporting said cylinder, a gear for 60 said cylinder, a hollow cylindrical bearing for said gear fixed to said framing, said bearing being supported at the end nearest said cylinder and being unsupported at the other end, a shaft for said cylinder extending loosely through said hollow bearing, and driving connections between 65 said gear and said shaft.
41. In a printing press, a reciprocating bed, an impression cylinder cooperating therewith, a gear for said cylinder mounted to turn upon a fixed axis, a driving wheel with a fixed axis having a 70 gear meshing with said cylinder gear, a bed rack, a driving pinion therefor, a shaft upon which said pinion is mounted, a pair of concentric gears on said shaft, angularly spaced segmental gears on said driving wheel adapted to mesh one at a 75 time with said concentric gears for imparting constant speed motion to said shaft in opposite directions at spaced intervals, and means for reversing the bed travel at each end of the stroke of the latter comprising a crank pin and a gear rotating with said crank pin and meshing with the gear on said driving wheel.
42. In a printing press, a reciprocating bed, two impression cylinders cooperating with said bed, gears for each of said cylinders, a driving wheel with a fixed axis having a gear meshing with both of said impression cylinder gears, a bed rack, a driving pinion therefor, a shaft upon which said pinion is mounted, a pair of concentric gears on said shaft, angularly spaced segmental gears on said driving wheel adapted to 1 mesh one at a time with said concentric gears for imparting constant speed motion to said shaft in opposite directions at spaced intervals, and means for reversing the bed travel at each end of the stroke of the latter comprising a crank 2 pin and a gear rotating with said crank pin and meshing with the gear on said driving wheel.
43. In a printing press, a reciprocating bed, two impression cylinders cooperating with said bed, gears for each of said cylinders mounted to 25 turn upon fixed axes encircled by said cylinders, means permitting relative movement between said bed and each of said cylinders toward and away from each other while maintaining a constant speed driving relation between said gears 30 and impression cylinders, means for raising and lowering said cylinders during the operation of the press, a driving wheel with a fixed axis having a gear meshing with both of said impression cylinder gears, a bed rack, a driving pinion 35 therefor, a shaft upon which said pinion is mounted, a pair of concentric gears on said shaft, angularly spaced segmental gears on said driving wheel adapted to mesh one at a time with said concentric gears for imparting constant 40 speed motion to said shaft in opposite directions at spaced intervals, and means for reversing the bed travel at each end of the stroke of the latter comprising a crank pin and a gear rotating with said crank pin and meshing with the gear on 45 said driving wheel.
44. In a printing press of the reciprocating bed type, an impression cylinder, a mechanism for raising and lowering said cylinder comprising a toggle with substantially aligned centers 50 when the cylinder is in raised position for re- 55 sisting downward movement thereof, and a different toggle with substantially aligned centers when the cylinder is in lowered position for re- 60 sisting upward movement thereof.
45. In a printing press, a reciprocating bed, an impression cylinder, a mounting therefor to support the cylinder above and in cooperating relation with said bed, and means for raising and 65 lowering said cylinder in timed relation with the bed movements, said means comprising a crank, a lever pivotally connected with the frame intermediate the crank and the cylinder, a lower link connecting the crank with one arm of the lever, and an upper link connecting the other 70 arm of the lever with the cylinder mounting, the crank and lower link being in substantial alignment when the cylinder is in raised position and the upper link being in substantial alignment with the pivotal mounting of said lever when the cylinder is in lowered position.
46. In a printing press, a series of three cylinders, sheet grippers on each of said cylinders, intermeshing gears on said cylinders, and means for driving both of the outer cylinders, the gear 75

on the intermediate cylinder comprising means for producing close mesh at the gripper position with each of the gears on the outer cylinders.

47. In a printing press, two sheet handling cylinders, a transfer cylinder interposed between them, and connections between each of the sheet handling cylinders and the transfer cylinder for driving the latter, said connections comprising means for registering the transfer cylinder with each of the sheet handling cylinders independently of the other and in alternation.

48. In a printing press adapted to print on sheets, two driven printing cylinders, gears on each of said cylinders, sheet transferring means between said cylinders, and connections between each of the gears on the printing cylinders and said sheet transferring means for driving the latter, said gears and connections being arranged to impart driving force to the sheet transferring means from one of said gears when receiving a sheet from the corresponding cylinder and from the other of said gears when delivering a sheet to the other cylinder.

49. In a printing press, a plurality of sheet carrying cylinders, grippers on each of said cylinders, a driving member, separate driving connections between the driving member and two of the sheet carrying cylinders, gripper transfer means for transferring a sheet from the grippers on one of said driven cylinders to the grippers on the other, and means for driving the transfer means exclusively from said driven cylinders in alternation.

50. In a printing press having a plurality of printing units each of which includes an impression cylinder, gripper transfer means for transferring a sheet from one impression cylinder to another, said means having slack therein and comprising means for removing slack at the point of transfer of a sheet to the forward impression cylinder, whereby the sheet is accurately registered upon that cylinder in a given relation to its position on a preceding cylinder, and a drive to each of said cylinders independent of the sheet registering means.

45. 51. In a printing press, a reciprocating bed having end reversal movement and intermediate constant speed travel, two impression cylinders

cooperating with said bed, a drive shaft, gearing between said drive shaft and said cylinders for driving both of the latter from a single intermediate driving element, said gearing comprising a vertically disposed gear adapted to rotate once for each reciprocation of said bed, and means for reciprocating said bed during its constant speed travel comprising the following elements, namely, angularly spaced gear segments rotating with said gear, a shaft, and concentric pinions on said shaft adapted to mesh with said gear segments for driving the shaft.

52. In a printing press, two printing cylinders, a transfer cylinder interposed between said printing cylinders, and operative connections between said printing cylinders and said transfer cylinder, said connections comprising means for producing close register at certain spaced intervals and looser register at other times, effective to impart driving force to said transfer cylinder from each of said printing cylinders alternately.

53. In a printing press adapted to print on sheets, two printing cylinders, gears on each of said cylinders, sheet transferring means between said cylinders, and driving connections between the gears on the printing cylinders and said sheet transferring means, said driving connections comprising means for producing accurate register at the position and instant of transfer, and loose register at other times, whereby the sheet transferring means is driven by one of said gears when receiving a sheet from the corresponding cylinder, and by the other of said gears when delivering a sheet to the other cylinder.

54. In a printing press, two impression cylinders, a transfer cylinder between said impression cylinders, a gear on each of said cylinders, the gear on the transfer cylinder meshing with both of the gears on the impression cylinders, sheet grippers on said cylinders, the gear of at least one of said cylinders comprising means located at the same angular position as the grippers on that cylinder for effecting accurate timing between that gear and a meshing gear at the transfer point.
